CHARLES T. DICKSON, OF WINNSBORO, TEXAS.

CRATE-CLAMPING MACHINE.

1,055,723.

Specification of Letters Patent. Patented Mar. 11, 1913.

Application filed June 24, 1912. Serial No. 703,490.

To all whom it may concern:

Be it known that I, CHARLES T. DICKSON, a citizen of the United States, residing at Winnsboro, in the county of Wood and State of Texas, have invented certain new and useful Improvements in Crate-Clamping Machines, of which the following is a specification.

My invention relates to new and useful improvement in crate clamping machines, and its object is to provide a machine or device that will hold the end boards and partition of a crate in a properly spaced parallel relation to each other during the process of nailing the side and bottom boards upon said end boards and partition.

A further object is to provide a device of the character described that will be strong, durable, simple and efficient and comparatively easy to construct and also one that will not be likely to get out of working order.

With these and various objects in view, my invention has relation to certain novel features of the construction and operations, an example of which is described in the following specification and illustrated in the accompanying drawing, wherein:

Figure 1 is a perspective view of the herein described crate clamping machine, the end members and center partition of a crate being shown in dash line mounted in the machine. Fig. 2 is a rear end view of the machine, the partition members being again shown in dash line, and Fig. 3 is a detail side view of two of the members which constitute a clamping unit.

Referring now more particularly to the drawing, wherein like reference characters designate similar parts in all the figures, the numeral 1 denotes a table or suitable support upon which the herein described machine is mounted.

The machine primarily consists of two frames, each provided with the same number of upright members, one of said frames being adapted to undergo a slight sliding adjustment relative to the other, by which movement the extremities of the end boards and partition members of the crate may be securely clamped between the respective upright members of the two frames. A pair of parallel bars 2, spaced a distance apart slightly less than the width of the crate to be formed by the machine, constitute the

primary members of one of said frame. Each of the bars 2 carries a plurality of equidistant upright clamping members 3, each of said members having approximately 60 the form of an inverted V, one leg of the member being vertical, and the other inclined. The clamping members 3 carried by the two bars 2 are arranged in opposite pairs. A rigid connection is formed between the opposite member 3 at the front end of the machine by a transverse bar 4. The parallel bars 2, with the upright bracket 3 and the connecting member 4 together form the adjustable frame of the machine 70 which has been previously mentioned.

The primary members constituting the stationary frame of the machine are two pairs of parallel bars 5 and 6, the former bars being respectively adjacent to the inner edges 75 of the bars 2, and the latter being respectively adjacent to the outer edges of the bars 2. The bars 6 will preferably be of angular form as is clearly shown in the drawings. The two pairs of bars 5 and 6 are rigidly connected at the rear extremity of the machine by a transverse bar 7, contiguous with the surface of the table 1 and rigidly secured to said surface by nails or other suitable means. The two members 5 and 6, which together form a guide way for each of the bars 2, are rigidly connected by three upright clamping members, which members are so spaced as to adapt them to form clamping pairs in conjunction with 80 the clamping members 3. The members 11 have the form of metal plates tapering slightly toward their upper ends, and having their lower extremities bifurcated to form lugs which are bolted respectively to 85 the bars 5 and 6. The front extremities of the bar 6 are joined by a transverse bar of round iron, the extremities of which are curved rearwardly, so as to space the central portion of the bar some distance from 90 the transverse brace member 4. A manipulating lever 10 has its lower extremity pivotally mounted at the center of the bar 9, said extremity being made to project slightly beneath the pivotal point of the 95 lever. An angular bracket 11 is mounted upon the cross bar 4 at a point opposite to the lower end of the lever 10, and a short swinging link 12 establishes a connection between the bracket 11 and the lower end of 100 the lever. The numeral 13 is made to designate 3 parallel boards which constitute

105

110

the end members and the central partition of a crate and are held supported in their proper spaced relation by the above described machine.

5 From the description above furnished, it is apparent that the members 3 and 8 constituting the clamping pairs may be adjusted to or from each other through a slight displacement by swinging the lever 10 from a substantially vertical to a substantially horizontal position or vice versa. When the lever 10 is swung downward, the clamping members 3 will be displaced toward the clamping members 8, and when 15 said lever is swung upward the reverse displacement of the clamping members 3 will result. The operation of the machine, therefore, consists merely in holding the lever 10 in a raised position while the cross 20 pieces 13 are being placed in the position clearly shown in Fig. 1. The lever 10 is then subjected to a downward displacement causing the extremities of the cross pieces 13 to be firmly gripped between the clamping 25 pairs formed by the members 3 and 8. After the clamping operation has been completed, the operator will be enabled to quickly nail the side boards and bottom boards upon the members 13 and can rest assured that the members 13 will remain in 30 their proper spaced relation while the nailing is being accomplished.

The machine shown is adapted for use in forming a crate having only one central partition, but it is obvious that the same principle may be employed in the construction of a machine adapted to form a crate having any desired number of partitions. It is also apparent that the proportion and 35 details of construction of the machine may be varied so as to adapt the machine to build crates and boxes of various sizes and shapes. The invention is, therefore presented as including all such modifications and changes 40 as properly come within the scope of the following claims.

What I claim is:

1. A crate clamping machine, comprising two frames, one of which is formed by a

pair of spaced bars rigidly connected, and 60 carrying a plurality of clamping members arranged in opposite pairs, and the other frame comprising two pairs of guide bars, each pair being associated with one of the bars of the first mentioned frame, means of 55 establishing a rigid connection between the two pairs of guide bars, a plurality of clamping members mounted upon each pair of guide bars, and adapted to act in conjunction with the clamping members carried by the first mentioned bars to form 60 clamping pairs, and means for manually subjecting the frame including the first mentioned spaced bars to a slight longitudinal adjustment relative to the other frame. 65

2. In a device of the character described, the combination with a pair of spaced bars, of a means establishing a rigid connection between said bars, two pairs of guide bars, the members of each pair being disposed at 70 each side of one of the first mentioned bars, a plurality of upright clamping members carried by the guide bars and rigidly connecting the members constituting each pair, the members carried by one pair being oppositely disposed to those carried by the other, a plurality of clamping members carried by each of the first mentioned pairs of spaced bars, the members carried by one of said bars being oppositely disposed to those 75 carried by the other, the clamping members carried by each pair of guide bars acting in conjunction with the clamping members carried by the bar mounted between said pair to form clamping pairs, and a manually operated means by which the two bars first mentioned may be simultaneously subjected to a displacement relative to the guide bars such as to vary the distance between the 80 members constituting each clamping pair. 85

In testimony whereof I have signed my name to this specification in the presence of two subscribing witnesses.

CHARLES T. DICKSON.
